Eaton

[11] Patent Number: Des. 368,071

[45] Date of Patent: **Mar. 19, 1996

[54] **PERPENDICULAR MOUNTING HYBRID
MODULAR ELECTRICAL POWER
CONNECTOR**

[75] Inventor: **Larry D. Eaton**, Fremont, Calif.

[73] Assignee: **TVM, Inc.**, Fremont, Calif.

[**] Term: **14 Years**

[21] Appl. No.: **28,822**

[22] Filed: **Sep. 22, 1994**

[52] U.S. Cl. **D13/147**

[58] Field of Search **D13/133, 146,
D13/147; 439/59, 76, 78, 79, 80, 82, 248,
552, 555, 562, 567, 572, 686, 844**

Primary Examiner—Joel Sincavage

[57] **CLAIM**

The ornamental design for a perpendicular mounting hybrid modular electrical power connector, as shown and described.

DESCRIPTION

FIG. 1 is a perspective view as seen from the front and upper left of a perpendicular mounting hybrid modular electrical power connector showing my new design;

FIG. 2 is a top plan view thereof;

FIG. 3 is a left side elevational view thereof;

FIG. 4 is a back elevational view thereof;

FIG. 5 is a right side elevational view thereof;

FIG. 6 is a bottom plan view thereof; and,

FIG. 7 is a perspective view as seen from the rear and lower right thereof.
